UNITED STATES PATENT OFFICE.

ARTHUR McDougall Duckham, of Waseda, Highfield, Ashtead, England,
Assignor to Isbell-Porter Company, of Newark, New Jersey, a Corporation of New York.

VERTICAL RETORT FOR THE PRODUCTION OF GAS BY THE CARBONIZATION OF COAL.

1,147,790.

Specification of Letters Patent. Patented July 27, 1915.

Application filed May 13, 1914. Serial No. 332,250.

To all whom it may concern:

Be it known that I, ARTHUR McDougall Duckham, residing at Waseda, Highfield, Ashtead, Surrey county, England, a subject 5 of the King of Great Britain, have invented certain new and useful Improvements in Vertical Retorts for the Production of Gas by the Carbonization of Coal, of which the following is a specification.

10 My invention relates to the construction and operation of vertical retorts for the production of gas by the carbonization of coal.

In vertical retorts for the carbonization of coal for the production of gas and where 15 the coke is more or less continually being discharged as a by-product from the lower end of the retort, there is a considerable waste of heat due to the temperature at which the coke leaves the retort.

20 The object of the present invention is to provide means not only for utilizing this sensible heat in the coke at the bottom of the retort before it leaves a continuously operated vertical retort for carbonizing coal, 25 but also recovering the greater part of the heat usually carried off by the waste gases passing from the heating flues of the retort, by causing said waste gases to pass through flues in contact with those around the lower 30 part of the retort through which pass the primary or secondary air or both, or cold producer gas used for heating the coal in the retort, and by such an arrangement dispose the air or gas to be heated between the 35 hot retort and the waste gas flues.

The invention is particularly adapted for use in connection with a retort in which the heating gases pass from the top toward the bottom of the retort, thereby permitting the 40 heating flues to be continued downward to constitute the waste gas flues surrounding or in contact with the air heating flues.

The invention consists of the structural embodiment of the above features, and in 45 specifically effective relative arrangement of parts, all of which will be more clearly described in the following specification, and particularly pointed out in the appended claims.

50 Reference is had to the accompanying drawing, forming part of this specification, in which similar reference characters indicate corresponding parts throughout the several figures.

In the drawings: Figure 1 is a vertical 55 longitudinal section of one of the retorts embracing the invention, taken on line I—I of Fig. 3; Fig. 2 is a transverse section on line II—II of Fig. 3; and Fig. 3 is a section taken on line III—III of Fig. 1. 60

Referring to the drawings, 1 constitutes the brick work or walls inclosing one of the vertical retorts 2, which is preferably rectangular in cross-section, having an upper charging opening 3 and a lower discharge 65 or outlet 4, said retort 2 tapering from outlet 4 to the inlet 3, as shown in Fig. 2. While I have shown only one retort, I wish it to be understood that my invention also embraces the connection of two or more retorts to form a bench of retorts in a single brick structure or walls, the same being a mere matter of multiplying the construction of retort herein shown and described, and readily understood by those skilled in the 70 art.

Adjacent to the bottom section and on two sides of the retort 2, is provided a series of superposed, horizontal regenerator or recuperator flues or tubes 5, 5, one end of 80 which flues 5, 5, communicates with a forward vertical flue 6, while their other ends communicate with the bottom of a rear vertical, or uptake flue 7, said flue 7 extending to near the top of the retort 2. The forward 85 vertical flue 6 is connected by means of a branch pipe 8 to a main 9, which supplies the cool producer gas along a bench of retorts, said branch pipe 8 being provided with the usual valve 10 for controlling and 90 regulating the supply of producer gas passing through the flues or tubes 5, 5.

The upper end of each of the uptake flues 7, 7, connects with a horizontal distributing flue 11, and said flue 11, as shown in Figs. 95 1 and 2, communicates with the upper ends and at one side of a series of vertical down-take heating flues 12, 12, adjacent to the side walls of the retort 2. The lower ends of the series of downtake flues 12, 12, communicate 100 by means of a lower horizontal flue 13, and vertical flue 14, to a main flue 15, which main flue leads to a stack, not shown. At the point of connection of the vertical flue 14 with the main flue 15, a damper 16 may 105 be provided for the purpose of controlling the draft or communication between said flues 14 and 15. The lower sections of the

flues 12, 12, and horizontal flue 13, and vertical flue 14, are adjacent to and on the outer sides of the flues 5, 5, as shown, and for purposes to be hereinafter described.

- 5 At the bottom of the retort 2, and on the outer sides of each set of flues 12, 13, and 14, is a second series of flues or recuperator tubes, 17, 17, each of said tubes having one of its ends 18 preferably connected and 10 valve controlled with the outside air, and its other end to a rear vertical uptake flue 19, parallel to and adjacent the uptake flues 7, as shown in Figs. 2 and 3. The upper end of each of the uptake flues 19, 19, is connected to a horizontal distributing flue 20, adjacent and similarly arranged with respect to the upper ends of the downtake flues 12, 12, as the horizontal flues 11, 11, for the purpose of conveying air to be mixed 15 with the producer gas issuing from the flues 11, 11, and burned in said flues 12, 12. The size of the openings connecting the horizontal flues 11 and 20 with the downtake flues 12, 12, may be controlled by adjustable dampers 21, 21, for regulating the supply of gas 20 or air into the downtake flues 12, 12, and degree of heating of the coal in the retorts 2, 2. Short vertical flues 23, 23, provided with outer closing caps 22, 22, are connected 25 to the horizontal flues 11 and 20, for the purpose of lighting the gas, inspecting the operation of the retort, or cleaning the flues, if found necessary.

The operation of the invention is as follows: Assuming cool producer gas is supplied from a main 9 to the different retorts, by branch conduits 8, which are controlled by valves 10, corresponding to the particular retort or coking chamber 2, the producer 30 gas is drawn by the draft of the stack from the conduit 8 into each of the forward vertical flues 6, from which said gas is distributed and passed through two series of horizontal heating flues 5, 5. The gas passing 35 through these flues 5, 5, is highly heated by the hot coke at the bottom of the retort or chamber 2 and flows into the lower ends of the uptake flues 7, 7, and ascends the same and is collected in the horizontal distributing flues 11, 11, from which said heated 40 gas passes, as indicated by the arrows in Figs. 1 and 2, in a downward direction into the retort heating flues 12, 12. The secondary air enters from the atmosphere through 45 the valve controlled openings 18 into a second series of heating or recuperating tubes 17, 17, said air being heated by the hot products of combustion passing through and out the flues 12 and 13, at the lower 50 section of the retort or chamber 2. The heated air flows out of said tubes 17, 17, into the bottom and up the flues 19, 19, into the horizontal air distributing flues 20, 20, from which said air passes downwardly as indicated 55 by the arrows, into the heating flues

12, 12, and mixes intimately with the heated producer gas issuing from the flues 11, 11, as shown in Figs. 1 and 2. The high heat produced by the combustion of the heated and mixed air and gas, is efficiently conveyed to the coal within the chamber or retort 2 throughout the coking zone of the coal, and the hot products of combustion pass downwardly between the two series of sets of tubes 5, 5, and 17, 17, and finally to the stack by the flues 18, 14 and 15, and in so doing, also assist in heating the producer gas passing through the tubes 5, 5. Thus it will be seen that the producer gas is not only heated by the heat of the coke passing 80 through the bottom of the retort or chamber 2, but also by the heat remaining in the products of combustion after having carbonized the coal in the retort 2.

The feeding of the coal into the top of 85 the retort and the extraction of the finished coke from the bottom end thereof, may be effected in any well known manner, and forms no essential feature of the present invention.

It is evident that the arrangement of air and gas recuperation or heating flues 17 and 5, may be reversed, that is, the gas may be conducted through the tubes 17 and the air through tubes 5, in which case the 90 gas will flow through the uptake flues 19 and distributing flues 20 and the air through the uptake flues 7 and distributing flues 11. Various other changes may be made to the 95 specific construction shown in the accompanying drawing without departing in any way from the spirit of this invention. For instance, instead of preheating the gas and air, the gas recuperation may be omitted and either the tubes 5 alone or together with 100 tubes 17, may be used for heating the air, or, either one of the rows of tubes 17 and 5 may be used for heating the primary air supplied to a gas producer, and the other 105 row of tubes for the secondary air. In such cases the air may be admitted to tubes 5 in a similar manner as shown for the tubes 17, while the fuel gas for heating the retort may be supplied in any other suitable manner, either in a heated or cold condition.

What I claim is:—

1. A retort for carbonizing coal for the production of gas comprising a vertical coking chamber having an upper coal charging inlet and a lower coke outlet or discharge, a 110 gas heating flue and an air heating flue adjacent the lower section or discharge of the vertical coking chamber, and a coal heating flue adjacent the vertical coking chamber above the air and gas heating flues and between the air and gas heating flues at the lower section of the coking chamber, said coal heating flue having an inlet communicating with the air and gas heating flues 115 near the top of the coking chamber and an 120

outlet for products of combustion at the bottom of the coking chamber.

2. A retort for carbonizing coal for the production of gas comprising a vertical coking chamber having an upper coal charging inlet and a lower coke outlet or discharge, separated horizontal air and gas heating flues at the bottom and adjacent the lower section or discharge of the vertical coking chamber, and a vertical coal heating flue adjacent the vertical coking chamber above the gas and air heating flues and between the separated air and gas heating flues at the lower section of the coking chamber, said coal heating flues having an inlet communicating with the gas and air heating flues near the top of the coking chamber and an outlet for the products of combustion at the bottom of the coking chamber.

20 3. A retort for carbonizing coal for the production of gas comprising a vertical coking chamber having an upper coal charging inlet and a lower coke outlet or discharge, a series of horizontal air heating flues at 25 the bottom and adjacent the lower section or discharge of the vertical coking chamber, a series of vertical coal heating flues adjacent the vertical coking chamber above the air heating flues and adjacent to the outer side 30 of the air heating flues at the bottom of the coking chamber, a series of gas heating flues at the bottom and on each side of the coking chamber and on the outer side of the coal heating flues, said coal heating flues having 35 an inlet communicating with the outlets of the air and gas heating flues near the top of the coking chamber and an outlet adjacent the air and gas heating flues at the bottom of the coking chamber.

40 4. A retort for carbonizing coal for the production of gas comprising a vertical coking chamber having an upper coal charging inlet and a lower coke outlet or discharge, separated and independent series of gas and

air heating flues at the bottom and adjacent 45 the lower section or discharge of the vertical coking chamber, coal heating flues adjacent the vertical coking chamber above the gas and air heating flues and arranged between the gas and air heating flues at the lower 50 section of the coking chamber, said coal heating flues having gas and air inlets communicating with the outlets of the gas and air heating flues near the top of the coking chamber, and an outlet for the products of 55 combustion adjacent the gas and air heating flues at the bottom of the coking chamber.

5. A retort for carbonizing coal for the production of gas comprising a vertical coking chamber having an upper coal charging 60 inlet and a lower coke outlet or discharge, a series of primary heating flues on opposite sides and at the bottom and adjacent the lower section or discharge of the vertical coking chamber, a series of coal heating 65 flues adjacent the vertical coking chamber above and on the same sides as the primary heating flues and on the outer side of the primary heating flues below the primary heating flues, a series of secondary heating flues 70 at the bottom and on each side of the coking chamber and on the opposite side of the coal heating flues from that of the primary heating flues, separate vertical flues connecting the primary and secondary flues with 75 the coal heating flues, said coal heating flues having inlets near the top of the coking chamber communicating with the outlets of the separated vertical flues and an outlet adjacent the primary and secondary heating 80 flues at the bottom of the coking chamber.

In testimony whereof I affix my signature in the presence of two witnesses.

AETHUR McDougall DUCKHAM.
